US0D1072841S

(12) **United States Design Patent** (10) **Patent No.:** **US D1,072,841 S**
Ayers et al. (45) **Date of Patent:** **** Apr. 29, 2025**

(54) **DISPLAY SCREEN OR PORTION THEREOF WITH A GRAPHICAL USER INTERFACE FOR REPORTING MEDICAL DATA**

(71) Applicant: **IDEXX Laboratories, Inc.**, Westbrook, ME (US)

(72) Inventors: **Jonathan W. Ayers**, Portland, ME (US); **Anestes G. Fotiades**, Portland, ME (US); **Robert B. Brazell**, Cape Elizabeth, ME (US); **David Dieffenbach**, Portland, ME (US)

(73) Assignee: **IDEXX LABORATORIES, INC.**, Westbrook, ME (US)

(**) Term: **15 Years**

(21) Appl. No.: **29/841,973**

(22) Filed: **Jun. 9, 2022**

Related U.S. Application Data

(63) Continuation of application No. 14/283,374, filed on May 21, 2014, now Pat. No. 11,551,789, which is a continuation of application No. 14/073,292, filed on Nov. 6, 2013, now abandoned, which is a continuation of application No. 11/733,353, filed on Apr. 10, 2007, now Pat. No. 8,585,590, which is a continuation-in-part of application No. 11/620,342, filed on Jan. 5, 2007, now Pat. No. 8,579,814.

(57) **CLAIM**

The ornamental design for a display screen or portion thereof with a graphical user interface for reporting medical data, as shown and described.

DESCRIPTION

The FIGURE is a front view of a display screen or portion thereof with a graphical user interface for reporting medical data.

The dot-dashed broken lines depict the display screen. The remaining broken lines depict portions of the graphical user interface. The broken lines form no part of the claimed design.
